ATTORNEY

UNITED STATES PATENT OFFICE.

NATHAN H. BALDWIN, OF LACONIA, ASSIGNOR OF ONE-HALF TO ROBERT M. APPLETON, OF LAKE VILLAGE, NEW HAMPSHIRE.

NECKTIE-FASTENER.

SPECIFICATION forming part of Letters Patent No. 270,173, dated January 2, 1883.

Application filed March 31, 1882. (No model.)

To all whom it may concern:

Be it known that I, NATHAN H. BALDWIN, of Laconia, in the county of Belknap and State of New Hampshire, have invented certain new and useful Improvements in Fasteners for Neckties and Scarfs, of which the following is a specification.

Gentlemen's scarfs as now used have a large narrow band which goes round the neck, and which is fastened at the front, below the scarf, to a fastening device of the shield of the same, while ties, bows, &c., are provided with an elastic loop, which is applied to the front button of the neckband. The neckbands of the scarfs are troublesome in use, while the elastic loops are soon worn out or broken, so that the ties or bows drop off the collar and require to be provided with new loops.

The object of this invention is to furnish an improved fastener for neckwear of all kinds by which the scarf, bow, or tie can be quickly placed in position and securely retained in position without getting out of order or wearing out; and the invention consists of a fastener for neckwear of peculiar construction, as hereinafter described and claimed.

In the accompanying drawings, Figure 1 represents a fastener shown as removed from the scarf or other article of neckwear and applied to the neckband of a shirt. Fig. 2 is a rear view of a scarf with my improved fastener attached, and Figs. 3 and 4 are detail side and top views of the fastener detached.

Similar letters of reference indicate corresponding parts.

A designates my improved fastener for neckwear of all kinds, which is made of brass, steel, or other wire of suitable thickness, or of any other material, and bent at its middle por-

tion into the shape of a loop, *a*, whereby it is attached to the shield of the scarf or bow, or to the body of the tie or bow.

From the center loop, *a*, extend in opposite directions slightly-curved arms *b*, the ends of which are bent so as to form eyes *d*, which prevent any injury of the arms to the neck of the wearer. The loop *a* is arranged at such an angle of inclination to the curved arms *b* that when the latter are placed over the neckband of the shirt or over the neckbands of the shirt and collar together they spring under the band and away from the neck without any possibility of pressing on or injuring the neck. By thus inserting the curved arms *b* of the fastener over the neckband of the shirt and collar bands the scarf, bow, or tie is quickly placed in position and retained on the shirt without the least inconvenience. Scarfs, bows, or ties provided with this fastener may also be used directly on the neckband of the shirt without using any collar, which is convenient during the summer season.

Having thus described my invention, I claim as new and desire to secure by Letters Patent—

A wire fastener for neckwear consisting of a central downwardly-projecting attaching-loop, adapted to be applied to the scarf, and laterally-projecting spring-arms adapted to overlap the neckband and spring outward against the inner face of the shirt-front when in use, substantially as described.

In testimony that I claim the foregoing as my invention I have signed my name in presence of two subscribing witnesses.

NATHAN H. BALDWIN.
